DESIGN FOR AN UPHOLSTERED CHAIR

James J. Modarelli, Berea, Ohio, assignor to The San Hygiene Upholstery Company, Akron, Ohio, a corporation of Ohio

Application February 13, 1947, Serial No. 136,879

Term of patent 3½ years

(CL. D15—11)

To all whom it may concern:

Be it known that I, James J. Modarelli, a citizen of the United States, residing at 73 Hamilton Street, Berea, Ohio, in the county of Cuyahoga and State of Ohio, have invented a new, original, and ornamental Design for Upholstered Chair, of which the following is a specification, reference being had to the accompanying drawing, forming a part thereof, wherein:

Fig. 1 is a plan view of an upholstered chair incorporating the new design;

Fig. 2 is a front elevation of the upholstered chair shown in Fig. 1;

Fig. 3 is an end elevation of the upholstered chair of Figs. 1 and 2.

I claim:

The ornamental design for an upholstered chair, as shown.

JAMES J. MODARELLI.
